UNITED STATES PATENT OFFICE.

EDWARD J. GULICK, OF ELKHART, INDIANA, ASSIGNEE TO C. G. CONN, LTD., A CORPORATION OF INDIANA.

WIND-MUSICAL-INSTRUMENT VALVE.

1,300,382.

Specification of Letters Patent. Patented Apr. 15, 1919.

Application filed July 8, 1918. Serial No. 243,750.

To all whom it may concern:

Be it known that I, EDWARD J. GULICK, a citizen of the United States, and a resident of the city of Elkhart, Elkhart county, Indiana, have invented certain new and useful Improvements in Wind-Musical-Instrument Valves, of which the following is a specification.

My invention relates to improvements in valves for wind musical instruments of the saxophone type, but not necessarily limited to use on a saxophone.

Valves of the character mentioned and described herein are usually closed by spring action and opened by finger pressure, and rapid valve action, whether in opening or closing the opening controlled thereby, as well as accurate and close adherence of the valve to its seat, are very essential for effecting the best results. All valves of the class under consideration and now in use have a pad, usually of fibrous material, secured thereto by a very pliable membrane of kid leather which overlies the pad and is generally non-adjustably and permanently fastened to the valve body or pad carrier in some manner, by adhesive or otherwise. In the course of time the pad cover becomes depressed, misshapen and somewhat wrinkled, or creased, whereby the valve closure efficiency is materially impaired. It then becomes necessary either to substitute a complete new valve or to free the pad membrane of its imperfections, and generally neither alternative is feasible when the requirement is most urgent.

An object of my invention is the production of a valve for wind musical instruments of the class mentioned in which the pad membrane or cover is readily removable and adjustable when imperfections therein develop. Another object of my invention is the production of improved means for detachably fastening the valve pad carried to the valve body. Other objects of my invention will be mentioned and described therein.

The preferred embodiment of my invention is well illustrated in the accompanying drawing, in which, Figure 1 shows a fragment of a saxophone with one or more of my improved valves applied thereto; Fig. 2 is a section through the saxophone body at one of the valve openings showing a valve seated over the opening; Fig. 3 is a plan view of the top of the pad carrier; Fig. 4

is a section taken diametrically through the pad carrier shown in Fig. 3; Fig. 5 is a plan view of the pad cover alone when spread out; Fig. 6 is a section taken through the pad, pad carrier and pad cover prior to fastening the pad cover to the carrier; Fig. 7 is a plan view of the pad cover after its flaps have been folded and tied; and Fig. 8 is a top plan view of the valve.

Similar numerals of reference indicate like parts and members throughout the several views on the drawing.

On the drawing the numeral 1 indicates the tubular body of a fragment of a saxophone which is provided with the lateral valve opening 2 the rim 3 whereof constitutes the seat for the valve hereinafter described. The numeral 4 indicates the valve cap, usually made of metal, which is provided with the endless flange 5 and a centrally located screw aperture 6. The numeral 7 indicates the valve pad carrier having the endless flange 8 and within which the valve pad 9, made of felt or other suitable material, is arranged, the pad being retained within the cup of the carrier by a cover 10 which may be made of kid leather, or other suitable flexible material, and fastened around the carrier 7 as hereinafter described.

The carrier 7 is centrally apertured at 11, which aperture is screw threaded and adapted to register with the aperture 6 of the valve cap 4, and adapted also to be engaged by a headed screw 12, when arranged within the valve cap, whereby the carrier 7 may be rigidly but removably confined within the flange 5 of the cap 4. The pad cover 10 may be cut from a single piece of kid leather and provided with a plurality of edge flaps 13, 13 on its circumference, each of said flaps being pierced by a flexible draw string 14, the string ends hanging free from two adjacent flaps. When the pad 8 is suitably positioned within the cup-like structure of the carrier 7 the pad cover 10 is laid over its face and the flaps 13 thereof are folded around the flange 8 of said carrier and upon the back of the latter, the string 14 being thereupon drawn taut and the ends thereof tied together. Thereafter, the assembled pad carrier 7, the pad 9 and pad cover 10 are fastened to the valve cap 4 by the screw 11.

Whenever the face of the pad cover 10 becomes imperfect for any reason, or adjust-

ment thereof is required; it is evident that the substitution of a fresh cover or the re-adjustment of the old one, may be readily effected.

5. I claim:

1. A valve for wind musical instruments comprising, a cap; a pad carrier; a pad; a flexible pad cover; adjustable means confining the pad cover to the pad carrier; and 10 means for detachably fastening the valve cap and pad carrier together.
2. A valve for wind musical instruments comprising, a cap; a pad carrier; a pad; a flexible pad cover removably fastened to the 15 pad carrier; and means for detachably fastening the valve cap and pad carrier together.
3. In a valve for wind musical instruments, a pad carrier; a pad carried by said 20 pad carrier; and a flexible pad cover overlying the pad and removably fastened to the pad carrier.
4. In a valve for wind musical instruments, a pad carrier; a pad; a flexible pad 25 cover; and a tension member carried by the

pad cover whereby the latter is fastened to the pad carrier.

5. In a valve for wind musical instruments, a pad carrier; a pad; a flexible pad cover provided with a plurality of flaps; 30 and a draw string connecting the cover flaps whereby the latter are adjustably confined upon the pad carrier.

6. In a valve for wind musical instruments, a valve cap adapted to receive a fastener member; a pad carrier adapted to receive a fastener member; a pad carried by the pad carrier; and a fastener member detachably securing said valve cap and the 35 pad carrier together.

7. In a valve for wind musical instruments, a valve cap provided with an aperture; a pad carrier provided with a screw threaded aperture; a pad mounted upon the carrier; and a headed fastener member 40 engaging the valve cap aperture and screwed into the pad carrier aperture.

In testimony whereof I have hereunto affixed my signature this 6th day of July, 1918.

EDWARD J. GULICK.
